CLAY B. ATKIN, OF KNOXVILLE, TENNESSEE.

SPECIFICATION forming part of Design No. 34,150, dated February 26, 1901.

Application filed February 2, 1901. Serial No. 45,783. Term of patent 7 years.

To all whom it may concern:

Be it known that I, CLAY B. ATKIN, a citizen of the United States, residing at Knoxville, in the county of Knox and State of Tennessee, have invented and produced a new and original Design for a Mantel, of which the following is a specification, reference being had to the accompanying drawing, which represents a face view of a mantel, showing my new design.

The base or lower portion A of the mantel is characterized by a horizontal projecting top portion or shelf a, having an ovolو molding and beaded fillet, below which is a horizontal panel b, provided with a central horizontal floral ornamentation consisting of a floral harp-shaped central figure c and two divergent lateral floral portions d, which are hook-shaped. Laterally from the curved ends of parts d are representations e of the fleur-de-lis. The sides or panels f are plain.

The back piece or upper portion B of the mantel is characterized by a top panel g, having an upwardly-convex central portion h, provided with a partly floral and partly arabesque ornamentation i, while a similar ornamentation j is arranged at the rounded corners of the panel. The horizontal projection or shelf k below the panel g is provided with a beaded fillet and an ovolو molding. Below 30 the shelf k is a rectangular panel flanked laterally by vertical ornamental or floral figures l in relief. On the sides of such panel are two vertical ornamental columns m, extending between the shelves a and k.
